UNITED STATES PATENT OFFICE.

WILLIAM F. BAUMHAUER, JR., OF QUINCY, ILLINOIS.

CARPET-STRETCHER.

SPECIFICATION forming part of Letters Patent No. 778,349, dated December 27, 1904.

Application filed February 4, 1904. Serial No. 192,062.

To all whom it may concern:

Be it known that I, WILLIAM F. BAUMHAUER, Jr., a citizen of the United States, residing at Quincy, in the county of Adams 5 and State of Illinois, have invented a new and useful Carpet-Stretcher, of which the following is a specification.

This invention relates to carpet-stretchers by means of which carpets may be stretched and held securely while being tacked; and it has for its object to provide a device of this class which shall possess superior advantages in point of simplicity, durability, and general efficiency, which may be easily secured 15 against displacement after the carpet which is being operated upon has been stretched to the desired tension, thus enabling the free edge of the carpet to be secured by means of ordinary carpet-tacks without necessity for 20 retaining it in its stretched position by a downward strain thereon by the knee of the operator or by other extraneous means.

A further object is to provide a carpet-stretcher having teeth which while they shall be able to firmly engage heavy carpets having 25 a very thick nap shall likewise be able to operate successfully upon thinly-woven carpets, such as ingrain carpets, without danger of the teeth or prongs piercing through such carpet into the carpet paper or lining which may have been placed underneath, thus tearing, displacing, or otherwise injuring the same.

With these and other ends in view, which will readily appear as the nature of the invention is better understood, the same consists in the improved construction and novel combination and arrangement of parts, which will be hereinafter fully described, and particularly pointed out in the claim.

In the accompanying drawings has been illustrated a simple and preferred form of embodiment of the invention, it being understood, however, that no limitation is made to the precise structural details therein exhibited, but that the right is reserved to any changes, alterations, and modifications which come fairly within the scope of the invention and which may be resorted to without departing from the spirit or sacrificing any of the 45 advantages of the same.

In said drawings, Figure 1 is a top plan view of a carpet-stretcher constructed in accordance with the principles of the invention. Fig. 2 is a bottom plan view of the same. Fig. 3 is a transverse vertical sectional view. 55

Corresponding parts in the several figures are indicated by similar numerals of reference.

In carrying out my invention I provide a block 1 of suitable dimensions, preferably 60 rectangular in shape. To the under side of said block are secured a plurality of longitudinally-disposed spacing-blocks 2 2, between which are secured strips of sheet metal 3 3, the lower edges of which are serrated to form 65 a plurality of teeth 4 4, said teeth having beveled or inclined rear edges 5 and vertically-disposed front edges 6, provided near their lower ends with shoulders or offsets 7, which are disposed a very short distance above 70 the points 8, which are formed by the convergence of the beveled rear edges and the lower portions of the vertical front edges of the teeth. Any desired number of these toothed strips may be used, said strips being 75 spaced suitably by means of blocks 2 2. It is obvious also that any suitable additional securing means may be used for the purpose of securing these strips in position without liability of their dropping out of position. 80 The main or face block 1 is provided at the front edge thereof with a hook 9, with which is connected a wire loop or band 10, having connection by means of a staple 11 with a lever 12, having a sharp point or prong 13, 85 which may be driven into the floor in advance of the edge of the carpet, while the block carrying the toothed strips is caused to engage the upper side or the nap of the carpet, when by strain upon the lever 12 the toothed block 90 will be forced in the direction of the wall, thus stretching the carpet to the desired degree of tension.

The block 1 is provided with a suitably-disposed opening 14, through which passes a 95 perforated sleeve 15, provided at its upper end with a boss 16. 17 designates a handle having a ferrule 18 and carrying a pin 19, which extends through the boss 16 and the threaded sleeve 15 and is of sufficient length 100

to be driven through the carpet and into the floor. When the carpet has been stretched or strained to the desired degree of tension, this pin is inserted through the perforated sleeve and boss and the point is driven into the floor, thereby securing the body of the carpet-stretcher positively against retraction or lateral displacement and enabling the operator to proceed with the application of tacks 5 by means of which the edge of the carpet is to be secured adjacent to the wall.

Having thus described the invention, what is claimed is—

In a device of the class described, a block 10 having a plurality of longitudinally-disposed

toothed strips, the teeth of said strips being provided with inclined rear edges and vertically-disposed front edges having shoulders or offsets near their lower ends, at a short distance from the extremities or points of the teeth.

In testimony whereof I have signed my name to this specification in the presence of the subscribing witnesses.

WILLIAM F. BAUMHAUER, JR.
